UNITED STATES PATENT OFFICE.

EDWARD H. GEORGIA, OF WATERBURY, CONNECTICUT.

STATION INDICATOR.

Application filed February 5, 1924. Serial No. 690,740.

To all whom it may concern:

Be it known that I, EDWARD H. GEORGIA, a citizen of the United States, and a resident of Waterbury, county of New Haven, and State of Connecticut, have invented certain new and useful Improvements in Station Indicators, of which the following is a specification.

This invention relates to station indicators and more particularly to an automatic electrically-operated device for trolley cars, subway trains, elevated trains, and the like, for changeably exhibiting the names of successive stations along the route.

One object of this invention is to provide a station indicator employing a continuous strip of sheet material wound upon a pair of drums, said strip being automatically advanced step-by-step as the successive stations are passed.

A further object of the invention is to provide a station indicator of the above nature in which one of the drums is intermittently rotated by the successive operations of an electromagnet.

A further object of the invention is to provide a station indicator of this nature, in which a flow of current will be sent momentarily through the electromagnet by the closing of a switch each time the car passes by a tripping block located alongside the rails.

A further object is to provide a device of the above nature which will be simple, inexpensive to manufacture, easy to install, accurate and reliable in operation, and very efficient and durable in use.

With these and other objects in view, there have been illustrated on the accompanying drawings, one form in which the invention may be conveniently embodied in practice.

Fig. 1 represents a view of the station indicator and circuit-closing device shown partly in section, partly broken away, and partly in diagram.

Fig. 2 is a sectional view of the display casing, and its operating mechanism, taken along the line 2—2 of Fig. 1, looking in the direction of the arrows.

Fig. 3 is a perspective view of a trolley car upon which the invention has been installed.

Fig. 4 is a sectional view of an alternative form of circuit-closing device.

Referring now to the drawings in which like reference numerals denote correspond-

ing parts throughout the several views, the numeral 10 indicates a trolley car adapted to travel upon a pair of rails 11, mounted upon ties 12. At a predetermined distance from the last street or station along the route of the car, provision is made of a tripping block 13 having a flat base adapted to rest on one of the ties 12. The block 13 has a laterally extending perforated ear 14 adapted to be secured to one of the ties 12 by means of a bolt 15 passing through said ear. The top of the tripping block 13 is curved, preferably in the arc of the circle, as shown more clearly in Fig. 1, and said curved surface is adapted to engage a curved shoe 15^a depending from the side of the car. The shoe 15^a is carried on the lower end of a switch-operating rod 16 slidably mounted within a tubular member 17, which extends up through the floor 18 of the car. The tubular member 17 is provided with a bracket 19 having a flange 19^a which is adapted to be secured to the under surface of the car by means of bolts 20. The shoe 15^a has an integral upwardly extending arm 21, said arm being hinged to the switch-operating rod 16 at the point 22.

The lower end of the switch-operating rod 16, above the hinge point 22, has a pair of leaf springs 23 riveted thereto, said springs being adapted to resiliently press upon opposite sides of the shoe-arm 21. By means of this construction, the arm 21 will be permitted to yield slightly when the shoe 15^a engages the tripping blocks 13, and undue shocks and possible breakage of parts is thereby prevented.

Located on the switch-operating rod 16 a short distance above the springs 23, is an integral collar 24 which serves to hold the lower end of a spiral spring 25, which surrounds the switch-operating rod 16. The upper end of the spring 25 is engaged by the lower end of the tubular member 17, the spring being of such a size that the shoe 15 will be pressed downwardly at all times. In order to prevent the switch-operating rod 16 from sliding out through the tube, the rod 16 is extended slightly above the tubular member 17, and is provided with a pin 26 adapted to rest on the top of said tubular member.

Mounted upon the floor of the car directly above the rod 16, is a switch support 26^a. A pair of horizontal resilient arms 27 and 28

are secured to the supporting member 26^a, the said arms being provided with a pair of opposed contact points 29.

The arms 27 and 28 are connected to the support 26^a by a pair of bolts 30 and 31, which pass through the support, and are locked in place by suitable nuts 32 and 33, said arms being insulated by means of a pair of tubes 34 and 35 of porcelain or other suitable material. Binding nuts 34^a and 35^a are threaded on the top of the bolts 30 and 31, and serve to connect the terminals of the switch to a pair of conducting wires 36 and 37. The wire 36 leads to one terminal of a source of current while the wire 37 leads to one terminal 38 of an electromagnet 39. The electromagnet 39 is adapted to actuate the signal mechanism, and is located in a casing 40 adapted to be secured to a wall of the car. The electric circuit is completed by a conducting wire 41 leading from the other terminal 42 of the electromagnet 39 to the source of current.

An auxiliary switch 43 may be provided in the conductor 41 if desired, so that when the motion of the car is reversed, for any reason, the station indicator may be disconnected. The disconnecting of the switch 43 when the car is reversed may be automatic or it may be done manually by the driver of the car.

The electromagnet 39 is adapted to be supported by means of a U-shaped bracket 44 secured to the wall of the casing in any suitable manner. The electromagnet comprises a cylindrical coil of wire 45 within which slides an iron core 46, said core 46 being rigidly mounted upon a core rod 47 journaled in a pair of shouldered discs 48 and 49 seated in the flanges 50 and 51 at the top and bottom of the cylindrical electromagnet respectively. The upper portion of the core rod 47 is provided with an enlarged bifurcated member 52 having a tooth member 53 pivotally mounted between its opposite arms. The tooth member 53 is provided with a pointed upper end adapted to engage between successive teeth of a ratchet 54 mounted on a shaft 55 journaled in the top of the indicator casing 40. The tooth 53 is adapted to be resiliently pressed at all times into contact with the ratchet 54 by means of a leaf spring 56 attached to the enlarged member 52, preferably by a screw 56^a.

Depending from the top of the casing is a pawl bracket 57 to which is pivoted a pawl 58 adapted to engage in the teeth of the ratchet 54 to prevent the latter from rotating backwardly.

The shaft 55 is provided with a drum 59 having flanges 60 and 61 at either end for receiving a continuous strip 62, said strip being preferably formed from transparent material having printed thereon a list of

the successive streets or stations along the route.

In the lower part of the casing, provision is made of a shaft 63 parallel to the shaft 55 and having a drum 64 rigidly mounted thereon, said drum 64 being somewhat smaller in diameter than the drum 59 previously described. The lower drum 64 has flanges 65 and 66 similar to the flanges 60 and 61 of the upper drum 59, and is adapted to receive the other end of the continuous strip 62. The front of the casing is closed by a flanged cover 67 fitting tightly about the edges of the casing and having a rectangular horizontal aperture 68 of such a size that the names of the stations can be readily observed by the passengers in the car. At the rear of the casing and in alignment with the rectangular aperture 58 are a pair of lamps 59^a which serve to illuminate the rear of the transparent strip 62.

In order to permit the continuous strip 62, containing the list of stations, to be rewound upon the lower drum, and to enable the indicator to be adjusted to any particular station, a pair of handles 76 and 77 are provided on the ends of the shafts 55 and 63, said handles being located outside the casing 40 for convenience in manipulation. In practice, the list of stations along the route in one direction will usually be duplicated on the continuous strip 62 in the reverse order, so that it will be unnecessary to manipulate the handles until the trolley car has completed a round trip.

In operation, when the car has left one station, and is approaching another, the tripping block 13 will strike the shoe 15^a and force the rod 16 upwardly. This will cause the terminals 27 and 28 to come into contact closing the switch and permitting a momentary current to flow through the electromagnet 39. The electromagnet thus energized will exert an upward pull upon the core 46 raising the core rod 47 and its tooth 53 upwardly a sufficient distance to rotate the ratchet 54 and the attached drum 59 forward one step. A portion of the strip 62 will thus be unwound from the drum 64 and wound up upon the drum 59, bringing the name of the next station into position behind the rectangular opening 68.

In Fig. 4, an alternative form of switch member is disclosed. This device comprises a U-shaped bracket 68^a having a flat base 69 secured to the floor of the car, and a depending tubular portion 70^a within the lower end of which a bell-crank lever 71 is pivoted. One arm of the bell crank lever 71 is inclined downwardly and is provided with a roller 72 at its lower end, said roller being adapted to engage the tripping blocks 13 previously mentioned. In this form of device, the contact elements of the switch comprise a pair of opposed vertical and horizon-

tal resilient arms 73 and 74 connected to the portion 70 in any suitable manner. The bell-crank lever 71 is provided with an arm 75 adapted to force the resilient terminal 74 into engagement with the terminal 73 whenever the roller 72 comes into engagement with said tripping blocks. When the roller 72 has passed beyond the tripping block, the bell-crank lever 71 will return to its original 10 position by gravity.

While there has been disclosed in this specification one form in which the invention may be embodied, it is to be understood that this form is shown for the purpose of 15 illustration only, and that the invention is not to be limited to the specific disclosure but may be modified and embodied in various other forms without departing from its spirit. In short, the invention includes all 20 the modifications and embodiments coming within the scope of the following claims.

Having thus fully described the invention, what is claimed as new, and for which it is desired to secure Letters Patent, is:

25 1. In a street or station indicator for a railway car or the like, a signal device, an electromagnet adapted to be intermittently energized to cause said signal device to indicate the successive streets or stations along 30 the route, an electric circuit for supplying electric current to said electromagnet; a switch in said circuit, said switch having a pair of horizontal arms with their extremities overlapping and slightly spaced 35 apart, a vertically slidable rod in alinement with said extremities, and a shoe resiliently connected to the lower end of said rod, said shoe being adapted to be engaged by an obstruction alongside the track where- 40 by the rod will be slid upwardly to close the electric circuit and energize the signal- actuating electromagnet.

2. In a street or station indicator for a railway car or the like, a signal device, an 45 electromagnet adapted to be intermittently energized to cause said signal device to indicate the successive streets or stations along the route, an electric circuit for supplying electric current to said electromagnet, 50 a switch in said circuit, a vertically slid- able rod mounted in the car frame for clos- ing said switch, a shoe member pivoted on the lower end of said rod, a pair of leaf 55 springs secured to said rod and engaging opposite sides of said shoe member, said shoe member being adapted to be engaged by an obstruction alongside the track where- 60 by the rod will be slid upwardly to close the electric circuit and energize the signal- actuating electromagnet.

3. In a street or station indicator for a railway car or the like, a signal device, an 65 electromagnet adapted to be intermittent-

ly energized to cause said signal device to indicate the successive streets or stations 65 along the route, an electric circuit for sup- 70 plying electric current to said electromag- net, a switch in said circuit, a tubular bracket mounted on said car, a rod slidable in said bracket for closing said switch, a 75 shoe member resiliently connected to the lower end of said rod, a collar on said rod below said bracket, a spiral spring located on said rod between said collar and said bracket for pressing said shoe downwardly, 80 said shoe being adapted to be engaged by an obstruction alongside the track whereby the rod will be slid upwardly to close the electric circuit and energize the signal- actuating electromagnet. 85

4. In a station indicator for a railway car, an indicating casing, a pair of drums in said casing, a continuous strip of dis- 85 playing material containing the names of successive stations along the route wound upon said drums, means for intermittently 90 rotating one of said drums to wind part of the strip thereon, said means comprising a ratchet connected to said drum, an electro- magnet-operated pawl for actuating said ratchet, means for momentarily passing a 95 current through said electromagnet, said means comprising an electric circuit for supplying electric current to said electro- magnet, a switch in said circuit, said switch having a pair of horizontal arms with their extremities overlapping and slightly spaced apart, a vertically slidable rod in alinement with said extremities, and a shoe resiliently 100 connected to the lower end of said rod, said shoe being adapted to be engaged by an obstruction alongside the track whereby the rod will be slid upwardly to close the electric circuit and energize the signal- actuating electromagnet. 105

5. In a street or station indicator for a railway car or the like, a signal device, an electromagnet adapted to be intermittently energized to cause said signal device to indicate the successive streets or stations along 110 the route, an electric circuit for supplying electric current to said electromagnet, a switch in said circuit, said switch having a pair of arms with their extremities over- 115 lapping and slightly spaced apart, a slid- able rod in alinement with said extremities, and a shoe resiliently connected to the lower end of said rod, said shoe being adapted to be engaged by an obstruction alongside the track whereby the rod will be slid up- 120 wardly to close the electric circuit and energize the signal-actuating electromagnet.

In testimony whereof, I have affixed my signature to this specification.

EDWARD H. GEORGIA.
